Mass., a corporation of Massachusetts

Application October 28, 1943, Serial No. 508,007

27 Claims. (Cl. 139—232)

This invention relates to improvements in filling mixing weft replenishing looms and it is the general object of the invention to provide improved means by which each of two shuttles may be replenished from a plurality of bobbin stacks of a multi-stack weft replenishing mechanism.

In order to prevent bar marks in the weaving of certain fabrics it is customary to employ two shuttles which are alternately active for short intervals. Thus, it is common practice to lay two picks of weft with one shuttle, the next two picks with a second shuttle, the third pair of picks with the first shuttle etc., so that any slight difference which may exist in the color of the two wefts will be blended. Much of the fabric requiring this kind of manipulation of the shuttles is woven on looms having a four-cell stationary magazine customarily arranged so that four different colors can be woven. When the fabric is of the same color and woven with two shuttles it is desirable that the full capacity of the magazine be utilized for replenishing the shuttles.

It has been proposed heretofore to utilize a pawl and ratchet operated cam which moves the stack selector progressively according to a given sequence so that bobbins are drawn from several stacks at a uniform rate. The cam as heretofore employed has been used with only one shuttle and has cooperated with a lever located on one side of the cam so that only those dwells or areas of the cam adjacent to the lever could be utilized for placing the selector. When it is desired to utilize a pair of stacks for each of two shuttles, however, this form of cam and lever arrangement will not effect drawing of bobbins from alternate stacks for each shuttle.

It is an important object of my present invention to provide means whereby a progressively fed multi-step cam can be utilized to position the selector with respect to two different pairs of stacks so that bobbins will be drawn alternately from the stacks of each pair of stacks for the replenishment of two shuttles.

It is a further object of my present invention to provide a stepped cam or stop to cooperate with two positioning members, such as the arms of a lever, and arrange the two members so that they engage opposite sides of the cam or stop. In this construction one of the positioning members engages the back of the cam to control the position of the selector with respect to one pair of stacks, while the other member engages the

front of the cam to position the selector with respect to the other pair of stacks.

In order that the cam or stop may present different surfaces to the devices which it controls provision is made for turning it by some part of the loom which has a movement incidental to a replenishing operation, such as the shaft which turns upon resetting of the magazine. Pawl and ratchet mechanisms have been employed in the past for this purpose, the pawl turning the ratchet and cam fastened to it at some time in the cycle of loom operations when the selector can safely be moved longitudinally. When two positioning members are to engage opposite sides of the cam provision must be made to have the cam so shaped that in its step by step movement and also in its alternate engagement with the members, each of the latter will change its position for each replenishing operation, otherwise one stack will become depleted more rapidly than the other. It is accordingly another object of my present invention to provide a single cam or stop so constructed that as it is moved step by step and is also engaged alternately by the positioning members the latter will shift the selector to draw bobbins uniformly from the several stacks. I have found that with four stacks a cam having eight angular movements to complete a rotation thereof will accomplish the aforesaid results if the contour provides a high dwell for two angular movements, a low dwell for the next two, a high dwell for the third pair of movements, and a second low dwell for the fourth pair of movements. In one of its settings such a cam will cause bobbins to be drawn from the stacks in a given order, but in another setting of the cam a different order results, but with either order each complete rotation of the cam will cause four bobbins to be drawn from each pair of stacks for the replenishment of the corresponding shuttle, and two bobbins will be drawn from each stack.

It is another object of the invention to provide a control for the cam feed whereby successive initiations of replenishment of the two shuttles shall be completed and whereby the replenishment of either shuttle, once initiated, will be completed even though an intervening replenishment of the other shuttle should occur.

With these and other objects in view which will appear as the description proceeds, my invention resides in the combination and arrangement of parts hereinafter described and set forth.

In the accompanying drawings, wherein a

convenient embodiment of my invention is set forth,

Fig. 1 is a side elevation of a weft replenishing mechanism as seen from the center of the loom provided with my invention.

Fig. 2 is an enlarged elevation of certain parts shown in Fig. 1,

Figs. 3 and 4 are front and rear elevations looking in the directions of arrows 3 and 4, respectively, Fig. 2,

Fig. 5 is a diagrammatic front elevation of a loom having my invention applied thereto,

Figs. 6 to 9 are diagrammatic views showing the cam and associated parts in different positions and illustrating a sequence starting with the cam in one position,

Figs. 10 to 13 are views similar to Figs. 6 to 9 but with the sequence starting with the cam in a different position,

Fig. 14 is an enlarged section on line 14—14, Fig. 1, showing the controller for the shield of the cam operating pawl, and

Figs. 15 and 16 are diagrammatic views showing the controller and shield in two different positions.

A weft replenishing mechanism of the type to which my present invention may be applied is shown in Fig. 1 wherein a loom frame 10 supports a reserve bobbin magazine R having four stacks 11, 12, 13 and 14 which are respectively provided with vertically reciprocable bobbin releasers 15, 16, 17 and 18. Each releaser has the lower end thereof associated with a bobbin cradle 20 which is normally empty but which is rocked in one direction when a releaser is raised to receive a bobbin from the associated stack, and is then rocked in the opposite direction when the releaser is depressed to discharge the bobbin and allow it to move to transfer position.

A color slide or selector 25 includes in its construction a shaft or rod 26 and a casting 27 from which project releaser lifter fingers 28 and 29, respectively. The front finger 28 is provided for the front pair of releasers 15 and 16 while the rear finger 29 cooperates with rear pair of releasers 17 and 18. The selector is movable longitudinally so that the fingers may register with the releasers one at a time.

A vertical rod 30 is provided for rocking the selector 25 about its axis in any of the four positions which it may assume. This rod is so controlled by well-known mechanism that it is moved downwardly when a shuttle in box B on the lay L under the magazine indicates weft exhaustion, thereby lifting the fingers 28 and 29 so that the releaser registered with the selector will be raised. At a later time rod 30 is moved upwardly to rock the selector 25 in the opposite direction and give the fingers 28 and 29 a downward motion for the purpose of depressing the previously raised releaser.

A transferer arm 33 of usual construction is pivoted on a fixed stud 34 and is operated by known mechanism to move downwardly to effect replenishment of a shuttle in box B. The upper end of each of the releasers is provided with a dog 37 which acts to rock a top shaft 40 when a releaser is depressed for the purpose of setting the magazine for replenishment. This shaft 40 is connected by a rod 42 to a shuttle position detector 44 pivoted on a fixed stud 45 carried by the magazine R. The lower part 46 of the positioner 44 may be provided with the usual cutter and includes a head which detects

the position of the shuttle to prevent transfer if the shuttle is too widely misplaced. In the event of a normal transfer, part 46 is pushed forwardly by the lay to effect a left hand rotation of the positioner 44 as viewed in Fig. 1 as the lay moves forwardly during a replenishing beat for the purpose of rocking shaft 40 back to its normal position.

The rod 26 has secured thereto a collar 50 having a groove 51 to receive a lug 52 on a lever 53 having a fixed pivot 54 on the magazine frame. A spring 55 acts on lever 53 and tends to move the same in a clockwise direction as viewed in Fig. 1 for the purpose of moving the selector 25 forwardly. A ratchet wheel 60 is secured to a lock wheel 61 cooperating with a yielding lock arm 62 and both wheels are mounted for rotation on a fixed stud 65. A lever 66 movable about a fixed pivot 67 is provided with a pawl 68 to turn the ratchet wheel 60. A rod 69 extends upwardly from lever 66 and is attached to an arm 70 on shaft 40. Whenever the latter shaft has a resetting motion as already described it will lift the pawl and cause a partial rotation of ratchet wheel 60 and the lock wheel 61.

The matter thus far described is of the usual construction and for further understanding of the same reference may be had to prior Patents Nos. 1,030,748 and 2,291,997. Each time the magazine is reset after being set for transfer, whether or not transfer ensues, the pawl will give the ratchet wheel an advance feeding motion which, by mechanism to be described hereinafter, determines the position of the selector 25.

In carrying my present invention into effect, I mount a cam 75 on the stud 65 and secure it to the ratchet and lock wheels. The ratchet wheel has eight teeth so that eight resetting operations of the magazine are required to produce a complete rotation of cam 75. I also provide the lever 53 with a second arm 76 which extends in front of the cam 75, or on the opposite side of the latter from the arm 77 of lever 53. The arms 75 and 77 are provided with studs, rolls, or the like 78 and 79, respectively, for engagement with the cam 75.

Referring particularly to Fig. 5 I have shown the left hand side of the loom as provided with gang G of shuttle boxes having top and bottom 50 shuttle boxes 80 and 81 each movable to active position in alignment with the shuttle race 82 on the lay L. The box B is at the opposite end of the lay and alternately receives shuttles S' and S² which are picked respectively from the boxes 80 and 81 when the latter are active. It is to be understood that the gang G may shift in a four-pick cycle so that shuttle S' is active for two picks and then shuttle S² is active for two picks, after which shuttle S' becomes active again for another pair of picks, and the sequence is repeated so that first two picks of the weft of shuttles S' is laid and then two picks of the weft of shuttle S², thereby effecting the previously mentioned blend. A connector 85 extends from the gang G or some part moving in timed relation with it across the loom and upwardly to be connected with the arm 86 of lever 53. This connector includes a strong tension spring 87 which may be connected directly to the arm 86 so that it works in opposition to the previously described spring 55. When shuttle S' is active the connector 85 is slackened and spring 55 is free to rock lever 53 in a clockwise direction as viewed in Fig. 1, but when gang G shifts and shuttle S² becomes active, a tension is set up

in the connector 85 which pulls down on the spring 87 and rocks lever 53 in a counter-clockwise direction. In the setting of the loom in which the shuttles run 2 and 2, therefore, lever 53 rocks to the right, two picks later rocks to the left, and after another two picks again rocks to the right, and continues to oscillate in this way at two pick intervals throughout the operation of the loom. During this oscillation of lever 53, first roll 78 will engage the left hand part of cam 75 as viewed in Fig. 1, and then roll 79 will engage the right hand side of the cam, these two rolls being alternately moved toward and away from the cam at regular two-pick intervals. The connector 85 is thus seen to be a controller for lever 53 and the rolls 78 and 79 in their movements relatively to cam 75, the connector moving lever 85 in a counter-clockwise direction as viewed in Fig. 1 and then allowing it to be moved in a clockwise direction by spring 55 as the shuttle boxes 80 and 81 shown in Fig. 5 shift first in one direction and then in the other.

The pawl turns cam 75 in a counter-clockwise direction as viewed in Fig. 2, see arrow M, Fig. 2, at each resetting operation of the magazine to give the cam a one-eighth turn. For purposes of description it may be assumed that the periphery of the cam has eight positioning areas, which when read clockwise around the cam, appear as follows: two low areas *a* and *f*, high areas *c* and *h*, low areas *e* and *b*, and high areas *g* and *d*. These areas change their angular position at each resetting of the magazine and also change their relation with respect to the rolls 78 and 79.

Figs. 6 to 9 set forth a sequence which starts with roll 79 against area *a* to register the selector with stack 11, see Fig. 6. At this time the shuttle boxes are down so that shuttle S' is active and spring 55 can move the selector to its extreme front position. If shuttle S' is replenished under these conditions, a bobbin will be drawn from the front stack 11, and there will be a one-eighth left hand turn of the cam so that area *b* is opposite roll 78. Upon arrival of shuttle S' in the gang G the latter will shift upwardly and there will be a downward pull on arm 86 and roll 78 will move against area *b* to permit lever 53 to swing to its rearmost position and register the selector with the rearmost stack 14, see Fig. 7. If under these conditions shuttle S' is replenished a bobbin would be drawn from the rear stack 14 and cam 75 would be given another one-eighth turn in a left hand direction to place area *c* in engaging position with respect to roll 79.

When shuttle S' is again replenished the area *c* and roll 79 will cooperate to register the selector with stack 12, see Fig. 8 and the next partial turning of the cam will place area *d* in controlling position. When lever 53 again rocks to the left roll 78 will engage area *d* and register the selector with stack 13 for the replenishment of shuttle S', see Fig. 9.

Since cam 75 is symmetrical the remaining half of its rotation will effect the same registry of the selector as that just described for the first half of the cam rotation, the areas *e*, *f*, *g* and *h* becoming successively operative and cooperating with their respective rolls to repeat the sequence already described.

It will thus be seen that a complete rotation of cam 75 starting in the position of Fig. 6 will draw two bobbins from each of the four stacks

and four bobbins from the front pair of stacks 11 and 12 to replenish shuttle S' and four bobbins from the stacks 13 and 14 to replenish shuttle S². The cam areas *a* to *h* become operative in their alphabetical order to effect a uniform depletion of reserve bobbins in the four stacks. The cam may be considered as a stop having two steps which in their different positions control rolls 78 and 79, and in turn determine the position of the selector.

The cam 75 can as a matter of fact be in any of its eight angular positions at the beginning of an eight step sequence and the effect of its continued partial rotations will be to draw bobbins from the stacks so that for eight replenishing operations two bobbins will be drawn from each stack and four bobbins will be drawn from each pair of stacks for the replenishment of the corresponding shuttle. Figs. 10 to 13 illustrate one of the several starting positions which may be assumed by cam 75 other than that already described. In these figures it is assumed that the sequence starts with area *f* in the controlling position for roll 79. Successive rocking of the cam in a left hand direction from this starting position will register the selector with the stacks in the following order: area *f*, stack 11; area *g*, stack 13; area *h*, stack 12; and area *a*, stack 14; etc. In this second sequence the order in which bobbins are drawn from the stacks is different from the first sequence, but only one bobbin is drawn from each stack for each half turn of cam 75 and the front pair of stacks supply bobbins for the replenishment of shuttle S' while the rear pair provide bobbins for shuttle S².

It will be found that if any of the areas *a* to *h* is made the starting point of a sequence, the selector will register with each stack once for a half rotation of cam 75. Thus, if the sequence starts with area *c*, bobbins will be drawn from the stacks 12, 13, 11 and 14 in the order named, and if the sequence starts with area *h* bobbins will be drawn from the stacks in the order 12, 14, 11 and 13.

By comparing the order in which bobbins are drawn from the several stacks over a comparatively long period of operation it will be seen that there are actually only two orders, namely, the first two described. The order starting with area *c* is the same as that for the order starting with area *a* except that it is out of phase with the latter order by two resettings of the magazine, and the order starting with *h* is similarly related to the order starting with area *f*.

If there should be some variation in the length of weft wound on the bobbins of the several stacks, it may happen that two successive transferring operations would replenish one of the shuttles and there would be a shift from one sequence to the other sequence. In the normal running of the shuttles two and two it may be assumed that there would be as many successive transfers for one shuttle as for the other, and that in a period of operation corresponding to the full capacity of the magazine the effect of shifting from one sequence to the other and then back to the first sequence will be to draw bobbins from the several stacks at a substantially uniform rate.

Where the bobbins are all wound with weft of practically the same length, however, the shuttles will require replenishment alternately and the exact order previously described will exist.

In the foregoing it has been assumed that each shuttle will have a period of activity for only two

successive picks. Certain features of the invention, however, will operate with patterns calling for a larger number of picks from one shuttle than from the other, although the full capacity of the pair of stacks corresponding to the less active shuttle may not be fully utilized. Under these last named conditions there might be several successive transfers for one shuttle during which the cam 75 in its step by step movement would effect two successive drawings of bobbins from one stack of the corresponding pair and then two successive drawings from the other stack of the pair. This condition could exist whether the successive transfers involved roll 78 or 79, and it is not necessary to shift the selector 25 from registry with one pair to registry with another pair.

If the pattern should call for a relatively wide band from shuttle S', for instance, followed by several short bands laid by both shuttles, and then followed by a wide band laid by shuttle S², successive transfers could take place with respect to the front pair of stacks when shuttle S' is weaving its wide band by cooperation of roll 79 with the back of cam 75 and successive transfers would occur with respect to the rear pair of stacks when shuttle S² is weaving its wide band due to cooperation between roll 78 and the front of the cam. There would be no need for the selector to shift registry with respect to the pairs of stacks in order to draw pairs of bobbins alternately from the pair of stacks corresponding to the shuttle weaving a wide band.

The structure thus far described operates satisfactorily if only one slide or releaser is in indicated or raised position at a time, a condition which prevails during the greater part of the weaving operation. It occasionally happens, however, that two releasers will be raised at the same time, such for instance, as releasers 15 and 17, one for each pair of bobbin stacks. Under such conditions the depression of releaser 15 and the ensuing transfer into shuttle S' will cause turning of the cam, but if the latter is in certain positions after its shift the selector will register with releaser 18 upon return to action of shuttle S². Therefore, the previously raised releaser 17 will not be depressed and the indication relative to shuttle S² will be lost. In order to insure return of the selector to registry with the previously raised releaser I provide the pawl guard shown in detail in Figs. 14, 15 and 16.

Referring to Figs. 1 and 15, the ratchet wheel is provided with a shield 100 mounted on stud 65 and having a guard 101 for pawl 68. An arm 102 of the shield is connected to a rod 103 attached to a shield controller designated generally at 105. This controller is mounted on rod 26 of the selector for angular movement thereabout and has a rail or bar 106 extending over all the upper or lifting lugs 107 of the releasers 15 to 18 and may have a reinforcing rib 108. Extending laterally from the rail are front and back arms 110 and 111, respectively, having depending bearing lugs 112 and 113, respectively, through which rod 26 passes and by which the latter supports the controller. The front and back bearings 114 and 115, respectively, on the magazine frame in which rod 26 turns and slides serve to position the bearings 112 and 113 with the rail 106 over the lugs 107. Bearing lug 113 carries an arm 116 pivotally connected to the upper end of rod 103, and a light spring 117 normally holds the rail 106 down on lugs 107 and shield 100 below pawl 68.

In operation, and assuming that all the releasers are down, the controller 105 and shield 75

100 will be in the position shown in Fig. 15. If shuttle S' should indicate exhaustion one of the front pair of releasers will be raised, such as releaser 15. As the latter rises its upper lug 107 rocks the controller in a counter-clockwise direction from the position of Fig. 15 to that of Fig. 16, depressing rod 103 and rocking the shield so that its guard 101 moves under the pawl 68 to move the latter away from ratchet wheel 60. Shuttle S' is then picked to the opposite side of the loom and shuttle S² becomes active, thereby shifting lever 53 as already described. If shuttle S' has ample weft it will be picked back to its box 81 with no change in the magazine and upon completion of the shift of gang G the selector, having shifted back to registry with releaser 15, will rock to lower the latter and set the magazine for a transferring operation, as usual, and at the same time will depress the previously raised lug 107 and permit spring 117 to lower the shield. During the subsequent rocking of shaft 40 pawl 68 will therefore advance the cam as already set forth without interference by the shield.

If, however, shuttle S² had indicated exhaustion in the previously described operation, one or another of the rear pair of releasers, such as releaser 18, would have been raised to place its lug 107 immediately under the already raised rail 106. The latter would therefore be held up by lug 107 of releaser 18 upon descent of releaser 15 and shield 100 would remain in position to prevent pawl 68 from turning the cam. When lever 53 again swings rearwardly roll 78 strikes the same part of cam 75 which it engaged when releaser 18 was raised, inasmuch as the cam has not turned, and the selector will still register with releaser 18 despite the replenishment of shuttle S'.

40 By reason of the controller 105 the shuttles can initiate their replenishments on successive arrivals at the magazine end of the loom with assurance that the initiated replenishing operations will be completed. Cam 75 will remain stationary so long as any releaser is up, and upon return of the corresponding roll 78 or 79 to the cam the selector will be in proper position to lower the previously raised releaser.

As already stated there are only two sequences 50 in which bobbins can be drawn from the bobbin stacks, and the interruption of one sequence when shield 100 prevents advance of the cam will bring the other sequence into action. It is not likely, however, that replenishment of the 55 shuttles on successive transferring beats of the loom will occur often enough to interfere seriously with the sequences. During by far the greater part of loom operation only one releaser will be raised at a time and the sequence of bobbin releasers will be interrupted only occasionally. When only one releaser is raised at a time the shield will be down in time to permit the pawl to advance the cam as set forth in the first part of this description.

From the foregoing it will be seen that I have provided simple means wherein a pair of shuttles may each be replenished from a pair of stacks of reserve bobbins by mechanism which includes a cam movable step by step to such positions that the placer mechanism causes the selector 25 to draw bobbins uniformly from the stacks of the magazine and draw bobbins from one pair of stacks for the replenishment of one shuttle and from the other pair of stacks for the replenishment of the other shuttle. This result is accom-

plished by the use of two positioning members, that is, the rolls 18 and 19, on a single carrier, such as the lever 53, which rocks back and forth to present the positioners alternately to the cam for successive resetting operations of the magazine, and the cam is so designed that its steps are related in such a manner with respect to the positioners during the successive step by step movements of the cam as the positioners oscillate that the bobbins are drawn from the stacks in correct sequence to deplete the stacks uniformly. It will also be noted that spring 55 will permit the selector to register with either of releasers 15 or 16 depending upon whether roll 19 engages a low or a high part of cam 75, and that spring 87, which is stronger than spring 55, yields to permit the selector to register with releaser 17 when roll 18 engages a high part of cam 75, but acts without necessary extension to move the selector to its rearmost position into register with releaser 18 when roll 18 engages a low part of cam 75. Also, if two successive transfers occur involving either pair of stacks when the corresponding positioning roll is on a low area adjacent to a high area next to be active, the lever 53 will be rocked by the cam 75 to shift the selector. This condition is true for each of the rolls 18 and 19, whether they pass from a low to a high area, or vice versa. It will further be seen that the controller 105 insures completion of an initiated replenishing operation for one shuttle even though the other shuttle should be replenished in the interval during which the first shuttle is temporarily in gang G.

Having thus described my invention it will be seen that changes and modifications may be made therein by those skilled in the art without departing from the spirit and scope of the invention and I do not wish to be limited to the details herein disclosed, but what I claim is:

1. In a weft replenishing mechanism having two pairs of stacks of reserve bobbins and a bobbin releaser for each stack operable by a selector movable to four different positions to register with the releasers, one at a time, a positioner operatively connected to said selector and moving first in one direction corresponding to one pair of stacks to move said selector toward the releasers of said one pair of stacks and then moving in the opposite direction corresponding to the other pair of stacks to move said selector toward the releasers of said other pair of stacks, and means cooperating with said positioner, depending upon the direction in which the positioner moves, to cause said positioner to register the selector with the releasers, one at a time, of the pair of stacks corresponding to the direction in which said positioner moves.

2. In a weft replenishing mechanism having two pairs of stacks of reserve bobbins and a bobbin releaser for each stack operable by a selector movable to four different positions to register with the releasers, one at a time, a positioner operatively connected to said selector and moving first in one direction corresponding to one pair of stacks to move said selector toward the releasers of said one pair of stacks and then moving in the opposite direction corresponding to the other pair of stacks to move said selector toward the releasers of said other pair of stacks, and means moving incident to replenishing operations of the mechanism and cooperating with said positioner when the latter moves in said

directions to locate said selector in the said four different positions thereof and, depending upon the direction in which the positioner moves, causing said positioner to register the selector with the releasers, one at a time, of the pair of stacks corresponding to the direction in which said positioner moves.

3. In a weft replenishing mechanism having two pairs of stacks of reserve bobbins and a bobbin releaser for each stack operable by a selector movable to four different positions to register with the releasers, one at a time, a positioner operatively connected to said selector and moving first in one direction corresponding to one pair of stacks to move said selector toward the releasers of said one pair of stacks and then moving in the opposite direction corresponding to the other pair of stacks to move said selector toward the releasers of said other pair of stacks, and means comprising a cam having high and low steps having movements incident to replenishing operations of the mechanism and cooperating with said positioner, depending upon the direction in which the latter moves, to cause said positioner to register the selector with the releasers, one at a time, of the pair of stacks corresponding to the direction in which said positioner moves.

4. In a weft replenishing mechanism having two pairs of stacks of reserve bobbins and a bobbin releaser for each stack operable by a selector movable to four different positions to register with the releasers, one at a time, a positioner operatively connected to said selector and moving first in one direction corresponding to one pair of stacks to move said selector toward the releasers of said one pair of stacks and then moving in the opposite direction corresponding to the other pair of stacks to move said selector toward the releasers of said other pair of stacks, and means comprising a rotatable cam having two opposite high steps and two opposite low steps moving angularly incident to replenishing operations of the mechanism and cooperating with said positioner, depending upon the direction in which the latter moves, to cause said positioner to register the selector with the releasers, one at a time, of the pair of stacks corresponding to the direction in which said positioner moves.

5. In a weft replenishing mechanism having two pairs of stacks of reserve bobbins and a bobbin releaser for each stack operable by a selector movable to four different positions to register with the releasers, one at a time, a positioner having two positioning members thereon, one for each pair of stacks, and operatively connected to said selector and moving first in one direction corresponding to one pair of stacks to move said selector toward the releasers of said one pair of stacks and then moving in the opposite direction corresponding to the other pair of stacks to move said selector toward the releasers of said other pair of stacks, a stop between said positioning members having high and low steps for alternate engagement with said positioning members, depending upon the direction in which the positioner moves, and means operating incident to replenishing operations of the mechanism to move said stop and change the relation of said steps with respect to said positioning members, said members cooperating with said stop, one at a time and depending upon the direction of movement of said positioner, to cause the positioner to register the selector with the releasers, one at a time, of the pair of stacks corresponding to the direction in which said positioner moves.

6. In a weft replenishing mechanism having two pairs of stacks of reserve bobbins and a bobbin releaser for each stack operable by a selector movable to four different positions to register with the releasers, one at a time, a positioner operatively connected to said selector and having two positioning members thereon, one member for each pair of stacks, said positioner moving first in one direction corresponding to one pair of stacks and then moving in the opposite direction corresponding to the other pair of stacks, a rotatable cam between said members for engagement with said positioning members, one at a time, an actuator for said cam giving the latter step by step movements incident to replenishing operations of the mechanism, and requiring eight steps to complete a rotation of said cam, opposite high dwells and opposite low dwells on said cam, each dwell corresponding to two consecutive replenishing operations of the mechanism and each member when engaging the cam cooperating with either a high dwell or a low dwell to cause the positioner to register the selector with one or the other of the releasers of the pair of stacks corresponding to the member engaging the cam.

7. In a weft replenishing mechanism having two pairs of stacks of reserve bobbins and a bobbin releaser for each stack operable by a selector movable to four different positions to register with the releasers, one at a time, a positioner operatively connected to said selector and having two positioning members thereon one for each pair of stacks, said positioner moving first in one direction corresponding to one pair of stacks and then moving in the opposite direction corresponding to the other pair of stacks, a cam requiring eight step by step movements for a complete rotation thereof, means operative upon a replenishing operation of the mechanism to give said cam a one step movement, and high and low dwells on said cam, each dwell being alternately related first to one of said members and then the other member, and a high dwell and a low dwell when cooperating with either member causing the positioner to register the selector with the releasers, one at a time, of the pair of stacks corresponding to the member.

8. In a weft replenishing mechanism having two pairs of stacks of reserve bobbins and a bobbin releaser for each stack operable by a selector movable to four different positions to register with the releasers, one at a time, a positioner operatively connected to said selector and having two positioning members thereon, one for each pair of stacks, said positioner moving first in one direction corresponding to one pair of stacks and then moving in the opposite direction corresponding to the other pair of stacks, a rotatable cam having opposite high dwells and opposite low dwells located between said members for engagement with said members, one at a time, depending upon the direction of movement of said positioner, and means effective upon an operation of said replenishing mechanism to advance said cam, the cam when moving a high dwell under either member moving the latter to cause movement of the selector from register with one releaser corresponding to the member to registry with the other member corresponding to the member.

9. In a weft replenishing mechanism having two pairs of stacks of reserve bobbins and a bobbin releaser for each stack operable by a selector movable to four different positions to register with the releasers, one at a time, a positioner

operatively connected to said selector and having two positioning members thereon, one for each pair of stacks, said positioner moving first in one direction corresponding to one pair of stacks and then moving in the opposite direction corresponding to the other pair of stacks, a cam between said members so proportioned as to be engageable with one member only at a time, one member engaging the cam when the positioner moves in said one direction and the other member engaging the cam when said positioner moves in said opposite direction, said cam having high and low dwells, and actuating means to move said cam to place the high and low dwells thereof successively in operative positions with respect to said members, each member when engaging the cam being moved thereby as the cam is moved by said actuating means to locate the selector in register with the two releasers, one at a time, of the pair of stacks corresponding to the member engaging said cam.

10. In a weft replenishing loom having two alternately active shuttles and operating with a pair of stacks of reserve bobbins for each shuttle, each stack having a bobbin releaser operated by a selector movable into register with the releasers, one at a time, controller means moving to one position when one shuttle is active and to another position when the other shuttle is active, positioning means for said selector to determine with which releaser said selector shall register, operating connections for the positioning means connected to the controller means and effective to move said positioning means and selector in one direction corresponding to one pair of stacks when said controller means moves to one position thereof when one shuttle is active and effective to move said positioning means and selector in the opposite direction corresponding to the other pair of stacks when the controller means moves to the other position thereof when the other shuttle is active, and means cooperating with said positioning means in whichever of said directions the latter moves and, depending upon the direction in which said positioning means moves, causing the latter to register the selector with the releasers, one at a time, of the pair of stacks corresponding to the direction in which said positioning means moves.

11. In a weft replenishing loom having two alternately active shuttles and operating with a pair of stacks of reserve bobbins for each shuttle, each stack having a bobbin releaser operated by a selector movable into register with the releasers, one at a time, controller means moving to one position when one shuttle is active and to another position when the other shuttle is active, positioning means for the selector including two members, one for each pair of stacks, to determine with which releaser said selector shall register, operating connections for said positioning means connected to said controller means and effective to move said positioning means in one direction corresponding to one pair of stacks when said controller means moves to one position thereof when one shuttle is active and effective to move the positioning means in the opposite direction corresponding to the other pair of stacks when said controller means moves to the other position thereof when the other shuttle is active, and stop means having two steps and moving to different positions and common to said members to cooperate with the latter, one at a time, said operating connections moving one of said members into engagement with the stop means when one

shuttle is active and moving the other member into engagement with the stop means when the other shuttle is active, and said stop means due to the different positions of the steps thereof cooperating with each member to cause the latter to locate the selector in register with the releasers, one at a time, of the pair of stacks corresponding to the member in engagement with the stop means.

12. In a weft replenishing loom having two alternately active shuttles and operating with a pair of stacks of reserve bobbins for each shuttle, each stack having a bobbin releaser operated by a selector movable into register with said releasers, one at a time, controller means moving to one position when one shuttle is active and to another position when the other shuttle is active, a pair of positioning members, one for each pair of stacks, operatively connected to said selector, a two-step stop common to said members to engage the latter, one at a time, operating mechanism for said members connected to said controller means and operative to cause one of said members to engage the stop when one shuttle is active and cause the other member to engage the stop when the other shuttle is active, and means causing said stop to present the two steps thereof in position for engagement with each member, each member cooperating with said two steps to register the selector with the releasers, one at a time, of the pair of stacks corresponding to the member engaging the stop.

13. In a weft replenishing loom having two alternately active shuttles and operating with a pair of stacks of reserve bobbins for each shuttle, each stack having a bobbin releaser operated by a selector movable into register with said releasers, one at a time, a two-step stop moving at each replenishing operation of the loom, a pair of positioning members, one for each shuttle and the pair of stacks corresponding thereto, for alternate engagement with said stop and each operatively connected to the selector, and control mechanism for said positioning members to effect movement of one of said members against the stop when one of said shuttles is active and effect movement of the other member against the stop when the other shuttle is active, each member when alternately engaging the two steps of the stop causing the selector to register with the releasers, one at a time, of the corresponding pair of stacks.

14. In a weft replenishing loom operating with two shuttle boxes moving alternately to active position and having a pair of stacks of reserve bobbins for each shuttle, each stack having a bobbin releaser operable by a selector movable into register with the releasers, one at a time, two positioners for said selector, one for each shuttle box and the pair of stacks corresponding thereto, a stop common to said positioners and having steps for engagement by said positioners, one at a time, said stop moving and in the different positions thereof cooperating with each positioner when in engagement therewith to register the selector with the releasers, one at a time, of the corresponding pair of stacks, and means moving in timed relation with said shuttle boxes to determine which positioner shall engage said stop.

15. In positioning mechanism for the selector of a weft replenishing mechanism having a plurality of bobbin releasers with which the selector registers, one at a time, said positioning mechanism comprising a lever connected to the se-

lector and having two arms, and a multi-step cam between said arms alternately engageable by said arms, said cam effective when the steps thereof engage one arm to cause the selector to register with certain of the releasers, one at a time, and when the steps engage the other arm causing the selector to register with the remaining releasers, one at a time.

16. In positioning mechanism for the selector of a weft replenishing mechanism having a plurality of bobbin releasers with which the selector registers, one at a time, said positioning mechanism comprising two control members both operatively connected to the selector to determine the position thereof, a stop common to said members provided with plural steps and engageable with said members, one at a time, the steps when engaging one of said members effective to cause the selector to register with certain of the releasers, one at a time, and when engaging the other member effective to cause the selector to register with the remaining releasers, one at a time.

17. In positioning mechanism for the selector of a weft replenishing mechanism having a plurality of bobbin releasers with which the selector registers, one at a time, said positioning mechanism comprising a pair of members operatively connected to and moving with the selector, a cam having a plurality of working surfaces located for engagement with said members one at a time, means to give the cam a step by step movement to position alternate working surfaces for engagement with one of said members and position the intervening working surfaces for engagement with the other member, one of said members when engaging the working surfaces corresponding thereto effective to register the selector with certain of the releasers, one at a time, and the other member when engaging the working surfaces corresponding thereto effective to register the selector with the remaining releasers, one at a time.

18. In a loom operating with two alternately active shuttles and having a pair of stacks of reserve bobbins for each shuttle and a selector to register with the stacks one at a time and wherein provision is made to cause the selector to initiate delivery of a bobbin from a pair of stacks when the corresponding shuttle is active and depleted and thereafter effect delivery of the bobbin after a period of activity of the other shuttle, the selector capable of initiating bobbin delivery when either shuttle is active so that simultaneous initiations of bobbin delivery can exist with respect to both pairs of stacks, two positioning members connected to said selector, a two-level stop common to said members, actuating mechanism for the members moving one of the latter against the stop when one shuttle is active and moving the other member against the stop when the other shuttle is active, the two levels of the stop cooperating with each member to cause registry of the selector with the two stacks, one at a time, corresponding to the member engaging the stop, feed means normally operative incident to each delivery of a bobbin to change the stop and levels thereof relatively to said members, and means operative whenever release of a bobbin is initiated in any stack to prevent said feed means from moving said stop, to the end that the selector when registered with any given stack of either pair of stacks and initiating bobbin release therein can return to registry with said given stack to effect bobbin delivery therefrom after effecting bobbin re-

lease from either stack of the other pair of stacks.

19. In a loom operating with two alternately active shuttles and having a pair of stacks of reserve bobbins for each shuttle and a selector to register with the stacks one at a time and wherein provision is made to cause the selector to initiate delivery of a bobbin from a pair of stacks when the corresponding shuttle is active and depleted and thereafter effect delivery of the bobbin after a period of activity of the other shuttle, the selector capable of initiating bobbin delivery when either shuttle is active so that simultaneous initiations of bobbin delivery can exist with respect to both pairs of stacks, two positioning members, one for each pair of stacks, connected to and moving with the selector as the latter moves from registry with any stack to registry with any other stack, a rotatable stop common to said members for engagement therewith one at a time, said stop having opposite high levels and opposite low levels, actuating mechanism for the members to move one of them against the stop when one shuttle is active and move the other member against the stop when the other shuttle is active, adjacent high and low levels of said stop when engaging either member causing the selector to register with the stacks, one at a time, of the corresponding pair of stacks, feed means normally operative incident to each bobbin delivery from any stack to change the stop and levels thereof relatively to said members, and means operative upon initiations of bobbin release in any stack to prevent said feed means from moving said stop, to the end that the selector when registered with any given stack of either pair of stacks and initiating bobbin release therein can return to registry with said given stack to effect bobbin delivery therefrom after effecting bobbin release from either stack of the other pair of stacks.

20. In a loom operating with two alternately active shuttles and having a pair of stacks of reserve bobbins for each shuttle and a selector to register with the stacks one at a time and wherein provision is made to cause the selector to initiate delivery of a bobbin from a pair of stacks when the corresponding shuttle is active and depleted and thereafter effect delivery of the bobbin after a period of activity of the other shuttle, the selector capable of initiating bobbin delivery when either shuttle is active so that simultaneous initiations of bobbin delivery can exist with respect to both pairs of stacks, two positioning members connected to said selector, a rotatable stop common to said members and engaging them one at a time, said stop having opposite high levels and intermediate opposite low levels, each level corresponding to two bobbin delivery operations and the stop requiring eight step by step movements for a complete rotation thereof, feed means normally effective incident to each of said eight step by step movements to advance said stop one-eighth of a turn, actuating mechanism to move each member against said stop when the corresponding shuttle is active, adjacent high and low levels when engaging either member effecting registry of the selector with the stacks, one at a time, of the corresponding pair of stacks, and means to prevent the feed means from advancing said stop whenever release of a bobbin is initiated in any stack, to the end that the selector when registered with any given stack of either pair of stacks and initiating bobbin release therein can return to registry with said

given stack to effect bobbin delivery therefrom after effecting bobbin release from either stack of the other pair of stacks.

21. In a weft replenishing loom operating with two shuttles and having a pair of stacks of reserve bobbins for each shuttle and a selector shiftable in opposite directions and registerable with the stacks one at a time and initiating bobbin release in a stack of one pair of stacks when the corresponding shuttle is depleted, then shifting to register with a second stack in the other pair of stacks and initiating bobbin release in the said second stack due to depletion of weft of the other shuttle and thereafter returning to register with and complete bobbin release from the first stack and then returning to registry with the second stack to complete bobbin delivery therefrom, a stop having surfaces at high and low levels, positioning means to cause the high and low surfaces to effect registry of the selector when the latter moves in one direction with the stacks, one at a time, of one pair of stacks and effect registry of the selector when the latter moves in the opposite direction with the stacks, one at a time, of the other pair of stacks, feed means normally operative incident to each bobbin delivery to advance said stop and change said surfaces relatively to said positioning means, and means to prevent said feed means from advancing said stop when bobbin delivery is completed from said first stack while bobbin delivery is initiated in said second stack.

22. A controller for the feed mechanism of the positioning cam for the selector which operates the bobbin releasers of a replenishing loom, said controller comprising preventer means movable from normal position to working position to make the feed mechanism inoperative with respect to the cam, and moving means connected to said preventer means and operated by any releaser to move said preventer means to working position.

23. A controller for the feed mechanism of the positioning cam for the selector which operates the bobbin releasers of a weft replenishing loom, the selector including a shaft in its construction, said controller comprising preventer means movable from normal position to working position to make the feed mechanism inoperative relatively to the cam, and a member connected to said preventer means and pivoted on said shaft and having a part for operation by each bobbin releaser to effect movement of said preventer means to working position.

24. A controller for the feed means of the positioning cam for the selector which operates the bobbin releasers of a weft replenishing mechanism from normal position to indicated position, preventer means movable from normal position to working position to prevent the feed means from moving the cam, and moving means pivoted on said mechanism common to said releasers and actuated by any releaser upon movement thereof to indicated position to effect movement of said preventer means to working position.

25. A controller for the pawl and ratchet of the feed mechanism of the positioning cam for the selector of a weft replenishing loom having bobbin releasers movable by the selector from normal position to indicated position, said controller comprising a shield for the pawl normally in non-shielding position, and means connected to said shield and operated by any releaser upon movement thereof to indicated position by the selector to move said shield to shielding position with respect to said pawl.

26. A controller for the pawl and ratchet of the feed mechanism of the positioning cam for the selector which moves the bobbin releasers of a weft replenishing loom from normal position to indicated position, said selector including a shaft in its construction, a shield for the pawl normally in non-shielding position, a member pivotally mounted on said shaft and connected to the shield, and means on the member common to the releasers to transmit a force from any releaser when the latter is moved to indicated position by the selector to the shield to move the latter to shielding position relatively to the pawl.

27. In positioning mechanism for the selector of a weft replenishing mechanism having bobbin releasers arranged in two pairs, the selector being registerable with said releasers one at a time and capable of moving any releaser registered therewith from normal to indicated position and subsequently return said releaser from indicated to normal position, said selector due to change of registry thereof relatively to the releasers capable of causing any two releasers to be in indicating position at the same time, said positioning mechanism comprising two control mem-

bers, one for each pair of releasers, and both operatively connected to the selector, a stop having steps at two different levels movable relatively to and common to said members and cooperating therewith alternately to determine the position of said selector, two steps at different levels when cooperating with one member effective to register the selector with the releasers one at a time of one pair of releasers, and two steps at different levels when cooperating with the other member effective to register the selector with the releasers one at a time of the other pair of releasers, said stop when in any one position and in alternate operative relation with said members effecting registry of said selector with feed means normally operative incident to each operation of the replenishing mechanism to advance said stop and alter the relation of the steps thereof with respect to said members, thereby causing said stop and members to effect registry of the selector with releasers other than said given releasers, and means controlled by any releaser in indicated position to prevent said feed means from advancing the stop.
